UNITED STATES PATENT OFFICE.

CECIL RAY CRARY, OF ST. CLAIR, MICHIGAN.

TURBINE-MUFFLER.

No 845,762.

Specification of Letters Patent.

Patented March 5, 1907.

Application filed March 29, 1906. Serial No. 308,767.

To all whom it may concern:

Be it known that I, CECIL RAY CRARY, a citizen of the United States, residing at St. Clair, in the county of St. Clair and State of Michigan, have invented certain new and useful Improvements in Turbine-Mufflers, of which the following is a specification.

This invention relates to new and useful improvements in mufflers for gas and other elastic-fluid engines. The construction contemplated pertains particularly to that type of muffler known as the "turbine-muffler."

The primary object of the present invention is to provide a muffler designed to reduce the back pressure of the residual gases in the engine-cylinder and to effect a thorough clearing of the cylinder after each action of the exhaust-valve, and this consideration is attained by creating suction in the muffler, the same being geared to the engine, so as to act as a high-head centrifugal pump.

A further object of the invention is to so thus dissipate and scatter the spent products of combustion from the engine-cylinder as to effectually reduce to a minimum the noise of the escape of said products.

The detail construction will appear in the course of the following description, in which reference is had to the accompanying drawings, forming a part of this specification, like numerals designating like parts throughout the several views, wherein—

Figure 1 is a front elevation of a muffler constructed in accordance with the present invention and showing the same as geared to the shaft of an engine. Fig. 2 is a section upon the line 2 2 of Fig. 1 looking in the direction of the arrow and showing the muffler in side elevation. Fig. 3 is a longitudinal section on the line 3 3 of Fig. 2 looking in the direction of the arrow, and Fig. 4 is a transverse section on the line 4 4 of Fig. 3 looking in the direction of the arrow.

In the practical embodiment of my invention I employ a suitable support comprising a base 1, which is secured by bolts to a suitable foundation, and a body portion 2, of a semicircular contour, for the reception of the muffler. The body portion 2 is provided with transverse end walls 3, which serve as bearings for the shaft of said muffler. The base 1 is provided at one end with an enlarged recessed boss 4, in which is journaled in any approved manner the end of a shaft 5, which may be the engine-shaft, or which may

be geared to the engine-shaft and driven therefrom.

The muffler-shaft 6 is journaled in the walls 3 of the support and is driven from the shaft 5 by gearing comprising a crown-wheel 7, mounted upon said shaft 5, which meshes with a bevel-pinion 8, carried upon the projecting end of the shaft 6.

The muffler comprises a stationary casing and a series of pistons or buckets carried by the shaft 6, which revolve within said casing. The casing comprises a plurality of sections, the outer sections of said casing being designated by the numeral 9 and constituting the end walls thereof and the intermediate sections being designated by the numeral 10.

The sections 9 are formed with a central apertured hub 11, through which the shaft 6 passes. Said sections are provided with concave inner surfaces, which are formed with an annular groove 12, that serves as a runway for the pistons or buckets of the muffler to be hereinafter described. The sections 10 are formed with a reduced central portion 13, which is apertured for the passage of the shaft 6 therethrough. The outer portions of the sections 10 are formed on each side with annular grooves 14, which coact with the adjacent grooves 14 and 12 (of the sections 10 and 9) in forming the runway for the pistons or buckets. The inner wall of each groove 14 and 12 is of less depth than the outer walls of said grooves, as is shown at 14^a in Fig. 3, and within said grooves a concentric space 15 is provided for the reception of the carrying-disks of the muffler pistons or buckets.

The sections 9 are severally provided with outstanding peripheral flanges 16, and the sections 10 are provided adjacent to the grooves 14 with similar outstanding flanges 16, which are arranged in spaced parallel pairs in each section 10. The flanges 16 confront one another throughout the structure of the casing and are united in opposed pairs by bolts 16^a. It will thus be seen that the adjacent sections coöperate to form independent turbine-cylinders, which are interconnected throughout the series.

One of the sections 9 and the opposing section 10 are provided with tangentially arranged grooves 17, which coact in confronting relation to form an inlet-port and are connected with a conductor 18, leading from the engine-exhaust, and the other sections 9 and the section 10 adjacent thereto are

formed with similarly constructed and arranged grooves, which are connected to an outlet-conductor 19.

The sections 10 are provided severally with 5 openings 20, extending therethrough between the grooves 14. The openings 20 are arranged on opposite sides in each adjacent section, and where several sections are employed said openings are in staggered relation throughout the series. It will thus be seen that the openings 20 afford communication between the several sections 10, the communication between said sections being interrupted by the muffler pistons or buckets, which severally act as valves with relation to the openings 20.

The spaces 15 confront one another in opposing pairs in the adjacent sections 10 and 9 and in this relation have located therein 20 disks 21 of constricted diameter. The disks 21 are severally provided with apertured hubs 22, occupying the width of the space between said sections. The hubs 22 are rigidly secured in any approved manner, 25 as by keys, to the shaft 6. The disks 21 carry muffler pistons or buckets 23, which are provided with bifurcated extensions 24, occupying the space between the reduced walls 14^a of the grooves 12 and 14, by which 30 the said buckets are secured to the constricted portions of the disks 21 through the agency of transverse securing-bolts 25.

The pistons or buckets 23 possess a similar arrangement throughout the casing and 35 travel in the same direction with one another and with the shaft 6. Said buckets are of a sufficient diameter to fit snugly within the runway formed by the grooves 12 and 14 in their confronting relation. For the purpose 40 of effecting a sealed joint between said buckets and said grooves the buckets may be provided adjacent their greatest diameter with elastic packing. I have not deemed it necessary to illustrate this last-named feature, 45 as it is clearly within the scope of the invention, together with other details of the arrangements and construction.

In operation the shaft 6 is driven at a high rate of speed from the shaft 5 and the spent 50 products of combustion are drawn into the casing by the suction of the rapidly-revolving pistons or buckets 23 through the conductor 18.

The waste gases thus introduced into the 55 casing travel approximately half of the circumference of the grooves, at which time they egress independently from the several buckets through the opening 20 to the adjacent section 10, in which they travel in the 60 same direction approximately half the circumference of the grooves and are then drawn through the opening 20 into the next adjacent section, and so on throughout the entire series of sections until they egress 65 through the port 19.

Having fully described my invention, I claim—

1. In a muffler a stationary casing comprising a plurality of connected sections, a shaft extending through said sections, pistons carried by said shaft and revolving between the opposing sections, the outermost sections being provided respectively with inlet and outlet ports, and the intermediate sections being provided with openings therethrough arranged in non-alined relation throughout the series. 75

2. In a muffler a stationary casing comprising a plurality of sections, arranged in transverse alinement and in confronting relation, a shaft extending through said sections, said sections being severally formed with annular grooves, the outer sections being provided respectively, with inlet and outlet ports and the intermediate sections being 85 formed with openings therethrough, arranged in staggered relation throughout the series and pistons carried by said shaft and occupying and traveling in the space between said grooves. 90

3. In a muffler a stationary casing comprising a plurality of sections, arranged in horizontal alinement and severally in confronting relation with the adjacent sections, a revolving shaft extending transversely 95 through said sections, means for operating said shaft from the shaft of an engine, one of the outer sections, being formed with an inlet-port, leading from the exhaust mechanism of an engine and the other of the outer 100 sections being formed with an outlet-port, the intermediate sections being severally provided with openings arranged in staggered relation throughout the series and affording communication therebetween, and 105 pistons carried by said shaft and occupying the spaces between the several sections in their confronting relation.

4. In a muffler a base, a stationary casing supported thereon, and comprising a plurality of transversely non-alined sections, arranged severally in confronting relation with the adjacent section, a shaft extending transversely through said sections and journaled in said base, the end sections of said casing 110 being provided respectively with inlet and outlet ports and the intermediate sections of said casings being formed with openings therethrough, arranged in staggered relation 115 and affording communication therebetween 120 and pistons occupying the space between said sections.

5. In a turbine-muffler a casing comprising a plurality of independent sections arranged in transverse alinement and severally 125 in confronting relation in adjacent pairs, said sections being united to one another and co-operating in confronting pairs to form independent turbine-cylinders, a shaft extending transversely through said sections, the end 130

turbine-cylinders constituted by the adjacent end pair of sections being respectively provided with inlet and outlet ports, the intermediate sections of the series being severally formed with openings extending therethrough and affording communication therebetween, said openings being arranged in staggered relation throughout the series, and pistons carried by said shaft and occupying and revolvably traveling in the space between the confronting sections.

In testimony whereof I affix my signature in presence of two witnesses.

CECIL RAY CRARY.
